UNITED STATES PATENT OFFICE.

CHARLES NELSON, OF NEW YORK, N. Y., ASSIGNOR TO S. STERNAU & COMPANY, OF NEW YORK, N. Y., A COPARTNERSHIP.

DESIGN FOR A CRUMB-SCRAPER.

42,925.

Specification for Design.

Patented Aug. 20, 1912.

Original application filed May 28, 1909, Serial No. 499,060. Divided and this application filed July 11, 1910. Serial No. 571,512. Term of patent 7 years.

To all whom it may concern:

Be it known that I, CHARLES NELSON, a citizen of the United States, and a resident of the borough of Brooklyn, county of Kings, city and State of New York, have invented a new, original, and ornamental Design for a Crumb-Scraper, of which the following is a specification, reference being had to the accompanying drawing, forming part thereof.

This application is a division of an application for patent for a new, original and ornamental design for table article filed May 28, 1909, and numbered serially 499,060.

The figure is a perspective view of a crumb scraper showing my new design.

The scraper is of rectangular shape, with an inclined wall on three sides, the edge of the wall being ornamented by a pattern consisting of alternate hemispheres or pearls and grooves at right angles to the edge. The handle springs out of one of the short sides, near the long side which has the wall, and is of rectangular cross-section, enlarged toward the free end, the end terminating in an ogee curve.

I claim:

The ornamental design for a crumb scraper, as shown and described.

CHARLES NELSON.
